UNITED STATES PATENT OFFICE.

CHARLES AUGUSTUS BEAUJON, OF CANAAN, CONNECTICUT.

BARB-WIRE-REEL SUPPORT.

1,119,566.

Specification of Letters Patent.

Patented Dec. 1, 1914.

Application filed April 9, 1914. Serial No. 830,630.

To all whom it may concern:

Be it known that I, CHARLES A. BEAUJON, a citizen of the United States, and a resident of Canaan, in the county of Litchfield, 5 and State of Connecticut, have invented a new and Improved Barb-Wire-Reel Support, of which the following is a full, clear, and exact description.

This invention relates to fences and has 10 particular reference to means for manipulating barb wire or the like in connection with spools.

Among the objects of the invention is to provide a reel support for use in connection 15 with a spool of barb wire, the reel support including a member extending through the axis of the spool and provided at each 20 end with a sleeve whereby such end may be supported by an operator or otherwise while the shaft is free to rotate with the spool.

A further object of the invention is to provide a shaft adapted to project through the spool and clamping devices coöperating with the shaft and bearing against the opposite 25 ends of the spool, clamping the spool to the shaft and also including a crank or the like for rotating the shaft while the supports therefor may be held stationary.

A still further object of the invention is 30 to provide a support for the purpose indicated which is adapted to be used in connection with metal reels, means being provided to maintain the supporting shaft properly centered in the reel.

The foregoing and other objects of the invention will hereinafter be more fully described and claimed and illustrated in the drawings forming a part of this specification in which like characters of reference 35 indicate corresponding parts in all the views, and in which—

Figure 1 is a vertical longitudinal section showing my improvement in connection with a metal reel; Fig. 2 is an end view 45 looking in the direction of the arrow 2; Fig. 3 is an end view looking in the direction of the arrow 3; and Fig. 4 is a detail of one of the clamping blocks described below.

The several parts of the device may be 50 made of any suitable materials, and the relative sizes and proportions, as well as the general design of the mechanism, may be varied to a considerable extent without departing from the spirit of the invention.

hereinafter more fully set forth and specifically claimed.

Referring more particularly to the drawings I show at 10 a shaft of sufficient length to extend through a reel R and projecting sufficiently far at each end to support loosely 55 thereon a sleeve adapted to be held by the operator or by other supporting means in a stationary position. The sleeve 11 is designed to be held by the operator in one hand, and while being so held said operator 60 may rotate the shaft by means of a crank 12 secured at the end at 13. At the opposite end of the sleeve 14 will be understood to be held by the other operator and is rotatably mounted permanently upon the shaft by 65 means of a fastening device 15.

At 16 is shown an enlargement of any suitable character, either as a continuous tube or as means at the ends of the sleeves 11 and 14 and serving to constitute points of 70 contact for the reel R or its bearing blocks. The enlargement is shown preferably in the form of a sleeve which is long enough to project entirely through the reel, and hence provides the necessary supports for the ends 75 of the reel and stiffens and reinforces the entire shaft. The enlargement 16 may be secured rigidly to the shaft 10 by any suitable means. When the device is used in connection with the common wooden reels for 80 barb wire, the holes provided at the ends of the spool are slightly larger than the diameter of the enlargement supports, and hence the shaft 10 and parts associated with the left hand end thereof may be slipped freely 85 through the reel, bringing a shoulder 17 snugly against the right hand end of the reel. Said shoulder is secured to or constitutes a part of the enlargement 16 and hence always turns with the shaft 10. The 90

opposite end of the enlargement 16 is threaded as 16' for the accommodation of a clamping disk 18 which, therefore, abuts against the end of the reel opposite the shoulder 17. A handle 19 is secured to the 100 disk and serves as a means for turning it on or off. At 20 I show a guard connected at 21 to the inner end of the sleeve 11 in any suitable manner. The guard 20, therefore, is normally stationary, being so held by the 105 sleeve 11, and may project radially from the sleeve in any direction and thence substantially parallel to the axle across the body of

wire on the reel. The purpose of this guard is to prevent injury to either of the operators due to the tendency of the wire to spring or fly from the spool during the rotation of the reel.

With the device as thus far described, the operation may be briefly set forth as follows: The clamping disk 18 being removed from the sleeve 16, the end 15 of the reel shaft may be slipped freely through the spool until the shoulder 17 strikes against the end thereof. Then the disk 18, which is adapted to slip freely over the end 15 and sleeve 14, is screwed up against the opposite end of the spool, clamping the spool to the enlargement 16 and shaft 10. The two sleeves 11 and 14 then being held by two operators or by other means in a stationary position, the wire may be wound upon the spool by the rotation of the crank 12, or if the wire is to be unwound from the spool, such action may take place freely, allowing the shaft and crank to rotate without obstruction.

Since barb wire reels are now being made of wire of a form somewhat similar to that illustrated in which there are crossed loops 21 at each end of the reel, these spools are formed with large rectangular openings in the center and hence not adapted for the use of a reel of any of the forms commonly employed in connection with wooden spools. I provide, therefore, a bearing block 22 for each end of the metal spool, each block having a central bearing hole 23 corresponding in position and size to the bearing hole in the usual wooden spool. These holes 23, therefore, receive the enlargement 16 in substantially the same way as is described

above. In order to prevent rotation of the bearing blocks 22 and thereby provide a substantially rigid clamping effect between the reel and the opposite shoulders 17 and 18, I provide each block with a projection 22' which extends inwardly toward the center 45 of the spool and substantially fitting the rectangular space formed by the crossed loops 21. While the bearing blocks may be made of any suitable material, when they are made of sheet metal as indicated, the 50 centers of the blocks surrounding the holes 23 constitute seats for the shoulders 17 and 18.

Having thus described my invention, I claim as new and desire to secure by Letters Patent:—

In a device of the character set forth, the combination of a spool having a rectangular central opening, a pair of blocks at the ends of the spool, each block having a projection 60 fitted into the rectangular end of the opening and having an axial hole therethrough, a shaft projecting through said axial holes, a shoulder secured to the shaft and fitted into one of said projections, a clamping disk 65 screwed into place in the other of said block projections, and serving to clamp the spool to the shaft, means to rotate the shaft, and stationary supporting means for the opposite ends of the shaft, substantially as set 70 forth.

In testimony whereof I have signed my name to this specification in the presence of two subscribing witnesses.

CHARLES AUGUSTUS BEAUJON.
